UNITED STATES PATENT OFFICE

137,804

DESIGN FOR A DART

Philip C. P. Booty, Chicago, Ill.

Application July 23, 1943, Serial No. 110,735

Term of patent 7 years

(Cl. D34—5)

To all whom it may concern:

Be it known that I, Philip C. P. Booty, a subject of the King of Great Britain, residing at Chicago, in the county of Cook and State of Illinois, have invented a new, original, and ornamental Design for Dart, of which the following is a specification, reference being had to the accompanying drawing, forming a part thereof.

Fig. 1 is a front end view of a dart embodying my new design;

Fig. 2 is a side elevational view of the dart shown in Fig. 1; and

Fig. 3 is a rear end view of the dart shown in Figs. 1 and 2.

I claim:

The ornamental design for a dart, substantially as shown.

PHILIP C. P. BOOTY.
